DESIGN FOR A TOY

William H. Biever, Philadelphia, Pa.

Application December 20, 1944, Serial No. 117,003

Term of patent 7 years

(Cl. D34—15)

To all whom it may concern:

Be it known that I, William H. Biever, a citizen of the United States, residing in Philadelphia, Philadelphia County, Pennsylvania, have invented a new, original, and ornamental Design for a Toy, of which the following is a specification, reference being had to the accompanying drawing, forming part thereof, in which:

Fig. 2 is a perspective view looking from the rear, a portion of the handle being broken away for convenience of illustration.

I claim:

The ornamental design for a toy, as shown.

WILLIAM H. BIEVER.
